LOW SILHOUETTE COMPRESSION SLIDER
Louis H. Morin, Bronx, N.Y.
(125 Beechwood Ave., New Rochelle, N.Y.)
Filed Feb. 20, 1963, Ser. No. 259,906
10 Claims. (Cl. 24—205.14)

This invention relates to sliders for use in connection with separable fastener stringers to couple and uncouple the same. More particularly, the invention deals with what I term a low silhouette spring-locking-type of slider, wherein the walls of the slider are normally cast in spaced relation to each other and the slider is compressed in assemblage of the slider upon the stringers of a fastener.

Still more particularly, the invention deals with a slider structure of the character defined, wherein the pull engaging yoke of the slider has a hook-shaped coupling engagement with one end of the slider wall and a single rivet is employed in assemblage of the yoke with the slider body and, further, deals with provision of means for support of the spring lock of the slider in hold-open position.

The novel features of the invention will be best understood from the following description, when taken together with the accompanying drawing, in which certain embodiments of the invention are disclosed and, in which, the separate parts are designated by suitable reference characters in each of the views and, in which:

FIG. 1 is a plan view of a slider made according to my invention, with parts of the construction broken away and parts in section.

FIG. 2 is a side and longitudinal sectional view through the slider as shown in FIG. 1, illustrating the normal cast position of the slider in full lines and indicating the compression of the slider in dotted lines, the spring lock of the slider being shown in operative position in full lines and in operative hold-open position in dotted lines.

FIG. 3 is an enlarged partial plan view of the contracted end portion of the slider, omitting associated parts and with part of the structure broken away and in section; 40

FIG. 4 is a sectional view on the line 4—4 of FIG. 2, omitting background showing.

Considering FIGS. 1 and 2 of the drawing, it will appear that the slider body comprises top and bottom walls 10 and 11, generally of the same peripheral contour, these walls being joined at the wide end of the slider in a connecting frog or web 12. The wall 11 has, centrally of the inner surface thereof, a raised platform 13, as noted in FIG. 2 of the drawing, and the wide end portion of the wall 11 reduced at its sides, as indicated at 14. This wall is shown in its normally cast position in full lines in FIG. 2 and in its compressed or use position in dotted lines.

The inner surface of the wall 10 has side scoop engaging flanges 15, generally of the contour indicated in dotted lines in FIG. 1 of the drawing, and terminating, as indicated at 15', to provide between 15' and the side walls 12' of the frog or web 12 the scoop admission passages, as with other devices of this type and kind.

The wide end portion of the top wall 10 has a raised platform 16, terminating in a shoulder 17, the platform 16 having an integral rivet forming portion 18 and centrally of the outer end of the platform is a raised rib or lip 19.

The wall 19 has, at the contracted end thereof, a raised and generally U-shaped platform portion 20, note FIG. 3 of the drawing. This portion has, at the contracted end, a crosshead 21, from which extend the parallel sides 22. The inner ends of the sides 22 form stop shoulders 23 in checking movement of the rounded pivot end 24 of a pull 25 in one directional operation of the slider, the

2

shoulder 17 checking 24 in movement of the slider in the opposed direction.

Adjacent the shoulders 23 and inwardly thereof, the top wall 10 has a transversely wide recess 26, which can be referred to as the hold-open recess, into which the pivot end 24 of the pull is adapted to seat when the pivot end is in the dotted line position of FIG. 2 in support of a spring lock, generally identified by the reference character 27 in hold-open position. It will be understood that the pivot end of the pull can be manually removed from the recess in normal operation of the slider.

The wall 10, at the contracted end of the slider and beneath the raised portion 20, has a transverse recess 28, which forms on the inner surface of the raised portion a shelf 29, adapted to be engaged by the hook end 30 of an elongated yoke 31. The hook end 30 includes a portion 32, which seats in a recess 33 formed in the raised portion 20 and part of the wall 10, as will clearly appear from a consideration of FIGS. 1, 2 and 3 of the drawing. 20 The yoke 31 seats on the exposed surfaces of the parallel sides 22 and conforms to the angular contour of these sides, as is clearly shown in FIG. 2 of the drawing. The other end of the yoke has an aperture 34 for receiving the rivet portion 18, including the riveted-over head 18' thereof.

The spring lock 27 has an elongated aperture 35, the end 36 of which terminates around the rivet 18; whereas, the other contracted end 37, note FIGS. 1 and 2, terminates in close proximity to the two scoop engaging lock elements 38 of the spring lock, note FIG. 4 of the drawing. The lock elements 38 operate in parallel apertures 39 formed in the wall 10, as clearly seen in FIGS. 2, 3 and 4 of the drawing. The elements 38 are offset, as indicated in FIG. 1, to align with and engage coupled scoops. Between the parallel apertures 39 is a rib 40, having an angular upper surface 41, which forms a stop engaged by the spring lock 27, or that part thereof disposed between the lock elements 38, as clearly seen in FIGS. 2 and 4 of the drawing.

In FIG. 2 of the drawing, the lock element 27 is shown in its operative position in full lines and in its inoperative or unlocked position in dotted lines. The spring lock, by virtue of the long aperture 35 provided therein, is free flexing and the lock elements 38 are fashioned to engage spaced scoops of stringers of a separable fastener. The rear edge 38' of one of the elements 38 serves as a stop adapted to strike against the walls 39' of the apertures 39 when 27 is in the locked position and a strain is applied to the stringers, tending to open the fastener, the spring lock 27 being capable of flexure or bowing slightly under the strain during this operation in assuring a positive check and lock of the slider on the stringer. The moment that this opening strain is removed, the lock element 27 will return to its normal locked position, as shown in full lines in FIG. 2 of the drawing. In connection with the foregoing, it must be kept in mind that, in manually operating the slider along the stringers in the coupling of the scoops or closing of the fastener, the elements 38 ratchet over the scoops and it is important 60 to provide free flexure of the lock spring 27 during this operation.

By providing a yoke, similar to the yoke 31, the assemblage of the slider parts is simplified, in that the hook end 30 of the yoke is simply engaged with the contracted end of the slider and the ends of the yoke 31 and spring 27 are passed over the rivet 18, with both of these members abutting the rib or lip 19, as clearly shown in FIG. 2, and the one riveting operation, as at 18', securely retains the parts in assembled relationship. The rib or lip 19 further serves to retain the spring lock 27 against movement in the direction of 19; whereas, the lock elements 38

engaging the apertures 39 maintain alignment of the spring lock on the slider wall at all time.

Having fully described my invention, what I claim as new and desire to secure by Letters Patent is:

1. A slider of the character described comprising a body having spaced walls joined at the wide end in a connecting web, one wall having at its ends raised platforms, an elongated yoke fixed to the platform at the wide end portion of the slider by a rivet portion, the other end of said yoke having a hook-shaped member engaging the platform and wall of the slider at the other contracted end thereof, a spring lock mounted on the rivet portion of the first mentioned platform and arranged within said yoke, said spring lock including at its free end lock means operating in an apertured portion of said wall of the slider in checking movement of a slider along stringers of a separable fastener, a pull having a pivot end operating in said yoke between said platforms and operatively engaging said spring lock in movement of the lock means into inoperative position, and said wall of the slider intermediate said platforms having a recess engaged by the pivot end of the pull in maintaining the spring lock in hold-open position. 10

2. A slider as defined in claim 1, wherein the platform at the contracted end of the slider is generally U-shaped in form as viewed in plan to form parallel sides, and said yoke fitting snugly upon and conforming to the contour of said parallel sides. 25

3. A slider as defined in claim 1, wherein the contracted end of said wall and the platform at said contracted end are recessed to receive the hook end portion of said yoke. 30

4. A slider as defined in claim 1, wherein the other wall of the slider body is normally formed in spaced relation to the first wall and moved into closer position to said first wall in compression of the slider when attaching the slide to stringers of a separable fastener. 35

5. A slider as defined in claim 4, wherein one of the walls of the slider body includes side flanges for guidance of scoops of a stringer into and through the slider body. 40

6. A slider as defined in claim 1, wherein the platform

to which the yoke and spring lock are riveted includes a rib engaging end portions of the yoke and spring lock. 4

7. A slider as defined in claim 1, wherein the lock means of said spring lock comprises a pair of lock elements, the apertured portion of said wall comprises a pair of apertures in which said elements operate, and said apertures being divided by a rib having an angular surface engaged by the spring lock in support of said lock elements in operative position.

8. A slider as defined in claim 7, wherein said spring lock includes an elongated aperture in providing free flexure of the spring lock in action of scoops upon said lock elements.

9. A slider as defined in claim 8, wherein the platform at the wide end portion of the slider includes means engaging the spring lock in retaining said spring lock in predetermined position on said platform.

10. In sliders of the character defined employing walls having wide and contracted end portions and a web joining the wide end portions of said walls with raised platforms at the wide and contracted ends of one wall, an elongated pull supporting yoke having a hook end engaging the platform at the contracted end of said wall, said yoke being apertured at the opposed end to engage a rivet portion on the platform at the wide end portion of said wall, a spring lock supported on said wall inwardly of said yoke and on said rivet portion, said wall being apertured to receive lock means on said spring lock, a pull having a pivot end operating between the platforms of said wall in movement of said spring lock into inoperative position, and means on the platform at the wide end of said wall engaging said spring lock in support of the spring lock against movement on said platform.
